WEIGHT CONTROLLED SEISMOGRAPHIC
COMBUSTION DEFLECTION

William Ross Stinnett, Dallas, Tex.

Application January 21, 1944, Serial No. 519,146

5 Claims. (Cl. 255—1.8)

1

The invention relates to a means and method of controlling combustion deflections in the art of seismic prospecting.

In the art of seismic prospecting the usual procedure is to drill a bore hole, deposit a charge of explosive therein and detonate such charge so as to set up deflections or wave vibrations in the earth which wave vibrations are transmitted through the earth as a function of the particular earth formation and reflected and refracted thereby so that detection of the waves of deflections permits of a determination of the nature of the earth formations.

It is imperative that the greatest possible force within certain limits be set up to cause such deflections but in the past a considerable amount of the force of the explosion has been dissipated by passing up the bore hole rather than being directed into the earth formations. The present invention contemplates a means and method whereby the resistance to travelling of the deflections up the bore hole is greater than that presented due to the earth formations so that the deflections seeking a path of least resistance will be directed into the earth formations rather than being dissipated up the bore hole.

It is one of the objects, therefore, of the invention to provide a combination anchor and discharge tool for seismic explosives so that the inertia of the anchor tool will tend to direct the force of the explosion downwardly and outwardly into the earth formations.

Another object of the invention is to provide a weight member approximating a weight of some five to ten thousand pounds which can be lowered into a bore hole and placed directly above an explosive charge so that the weight of the tool is available to resist the transmission of force from the explosion upwardly through the bore hole.

Another object of the invention is to provide a combination drilling tool and removable casing for seismic exploration bore holes.

Another object of the invention is to provide a combination anchor and discharge tool where the explosive is connected to the anchor portion of the tool ready for discharge so that the anchor portion will resist the force of the explosion tending to travel upwardly in the bore hole.

Another object of the invention is to provide an anchor and discharge tool where the explosive to be discharged is to be deposited in the tool and the force of explosion thereof directed by the tool into the earth formation.

Another object of the invention is to provide a

2

drilling tool and plain end casing made up of a plurality of sections to be interfitting end to end in the drilling of a seismic explosive bore hole.

Another object of the invention is to provide drilling and shooting equipment, including a slip socket connection for drill rods, used in drilling seismic exploration bore holes.

Another object of the invention is to provide a weight controlled method of discharging seismic explosive charges to obtain a maximum deflection of the earth.

Other and further objects of the invention will be readily apparent when the following description is considered in connection with the 15 accompanying drawing wherein:

Fig. 1 is a vertical sectional view of a bore hole being drilled with the particular type of drill and casing provided by the invention.

Fig. 2 shows the same bore hole with the combination anchor and discharge tool landed in position ready for discharge of the explosive.

Fig. 3 is a vertical sectional view through the anchor and discharge tool.

Fig. 4 shows a modified form of anchor and 25 discharge tool which is particularly adapted for shallow bores.

Fig. 5 is a sectional view of an earth formation with the invention of Fig. 3 in use and illustrating the manner of directing the deflections of the 30 explosion downwardly into the earth.

In Fig. 1 a well bore 2 has been drilled in the earth 3 by means of a drill bit assembly 4 including a projection 5 for drilling a small bore 6, generally known as a rat hole, ahead of the larger 35 diameter bore 7. Bores such as this which are used to set off the explosive in the art of seismic prospecting vary from a few feet to possibly one hundred feet or more in depth and they are drilled by rotating the bit 4 by means of a string of rods or pipe 8 which are connected by the slip joint 10. Any suitable source of power may be used at the surface to rotate the rod or pipe 8 so as to apply weight thereto and cause the bit to advance into the earth.

In order to prevent the earth from caving into the bore it is not unusual to provide a string of pipe or casing 12 which will be positioned in the bore hole. It is desirable in many instances to have this casing advanced into the hole to prevent 45 caving as the drilling proceeds and in the present arrangement this course is being followed and it will be noted that the lower end 13 of the casing section 14 is opposite the bit assembly 4. The casing is usually rather light in weight or has 50 a thin wall which may not be susceptible to

threading in order to connect the section 15 of casing to the section 14. To accomplish this in the present procedure a collar 16 is provided having a rib or flange 17 projecting from its outer periphery. This collar will fit snugly into the end of the casing section 14 and permit the pipe section 15 to be positioned over the other edge of the collar. In this manner the pipe sections 14 and 15 are retained in alignment and held in position.

In order to cause the casing to advance downwardly with the drill bit a drive collar 20 may be affixed to the pipe or rod by means of a cross bolt or pin 21 and this collar carries a bushing 22 having the antifriction bearings 23 disposed between it and the collar 20. This bushing has a shoulder 24 to fit the upper end of the section of the casing and it seems obvious that as the drill rod and bit are lowered the collar 20 will rotate therewith while the bushing 22 will remain non-rotatable with the casing but the downward pressure will tend to drive the casing down simultaneously with the drilling operation.

It will be noted that the body 4 of the drill bit assembly is of slightly less diameter than the inside of the collar 16 so that the drill bit may be removed therethrough. Any suitable number of sections of casing, 14, 15, etc. may be added as the drilling progresses by incorporating additional lengths of the drill pipe and additional lengths of casing.

After the drilling has been completed and preparations are made for setting off the explosion a combination anchor and discharge tool 25, best seen in side elevation in Fig. 2, will be lowered into the well bore by the string 8 of pipe or rods. What might be said to be a slip or toggle joint 10 constitutes a squared shank 26 best seen at the top of Fig. 3 which fits into a non-circular opening 27 in the lower end of one of the rods and a connecting pin 28 is then passed through the parts to retain them in position. The string of pipe or rods 8 may have any desired number of these connections to obtain the necessary length.

The tool 25 is best seen in section in Fig. 3 and includes a massive body 30 which is preferably made of iron, steel or a suitable heavy material because it is intended that this body may have a weight of from five to ten thousand pounds so as to dispose its weight on top of the explosive cartridge 31. The cartridge may be deposited in the rat hole 6 independently of the anchor member, but preferably the two are combined together to form a combination anchor and discharge tool wherein the explosive cartridge 31 is positioned against the base 32 of the anchor member and held in place by the retainer springs 33. The cartridge 31 is preferably made up of the explosive charge 34 held in position by a closure plug 35 and carried by a support plate 36. A suitable detonator 37 may be connected to the electric wires 38 which extend through the passage 39 and upwardly in the well bore to the surface where the circuit may be closed to initiate the detonation.

This assembly will be lowered into the well bore and positioned as seen in Fig. 2 so that the weight not only of the drill rod or pipe 8, but also the weight of the anchor member 30 will be deposited directly upon the explosive charge 31. With the parts in this position the explosive charge will be detonated so that the force of the explosion will be directed into the earth formation in the manner illustrated diagrammatically in Fig. 5. It seems obvious that the massive body 30 of the anchor tool will present a much greater resistance

to the transmission of force upwardly through the well bore than will the face of the earth formations about the rat hole so that when the explosion occurs the greater inertia of the anchor member will tend to prevent the force of the explosion from being dissipated upwardly in the bore hole and will cause a maximum of deflection of the earth formations as indicated by the lines 40 of Fig. 5. In this manner greater deflections will be set up in the earth than could otherwise be obtained with the same or a larger charge of explosive so that the recordings will be more definite due to the fact that the well bore has been sealed by the anchor member and effective resistance to dissipation of the force of the explosion provided.

It is desirable to recover the casing 12 from the bore hole after the explosion has occurred and to this end suitable stops 41 may be carried by the anchor member in the form of blocks 42 deposited in the recesses 43 and normally urged outwardly by the springs 44. A stop pin 45 may be provided to limit the outward movement of the stops. In this manner when the tool passes below the lower end 13 of the casing as best seen in Fig. 5 the stops will snap outwardly and when the tool is lifted the casing will be lifted thereby and can be readily removed from the well bore.

It seems obvious that the mass of the weight 30 may be varied as desired depending upon the depth of the bore, the size of the explosive shot and upon other circumstances and conditions. In actual operation the device has been found to be exceptionally efficient and results in improved recordings over those previously obtained where no anchor weight was utilized.

Very often shallow bore holes are utilized and Fig. 4 shows such a shallow bore 50 as having been formed by forcing the combination anchor and explosive tool 51 into earth 52. This tool may be rotated by a pipe or rod 53 having the connection 10 to the tool 51.

The lower end of the tool 51 has a tapered bore 53' therein so that the lower edge 54 tends to penetrate the earth. This tapered opening 53' has a chamber 56 therein adjacent its upper end to receive the explosive cartridge 57 which may be retained in position by a nail or retainer pin 58. The detonator 59 in the cartridge is connected by the wires 60 to a battery or other source of energy to set off the detonation. It seems obvious that the weight or mass of the member 51 will effectively direct the force waves or energy of the explosion outwardly and downwardly into the earth formation due to the great inertia thereof so that a sharp and efficient deflection of the earth is obtained.

In some instances the earth formation is rather hard and firm and difficulty might be encountered in forcing the swaged drill 4 through such a formation. In such a circumstance a conventional drill bit might be used to drill, say a four inch hole, and then the bit 4 used to enlarge the hole to, say six inches. The swaged lower end of the bit 4 would thus pack the earth material firmly and no casing or pipe would be required.

It seems obvious that a suitable truck carrying a hoisting boom or davit and suitable mechanism for rotating the pipe 8 can be provided so that the entire assembly can be hoisted into or out of position and rotation imparted thereto.

Broadly the invention contemplates a means and method of increasing the efficiency of seismic explorations.

What is claimed is:

1. In drilling and shooting equipment for seismic prospecting including a drill rod, an explosion discharge tool secured to said drill rod and adapted to be lowered by said drill rod into a bore having a casing therein, said bore being provided with a drill hole at the base thereof, said tool comprising a massive body having an exterior diameter slightly less than the interior diameter of said casing, a cartridge mounted beneath said body, an explosive charge confined within said cartridge, means for detonating said charge, said cartridge being forced into the drill hole by said body whereby the force of the explosion of said charge will be directed downwardly into the earth due to the inertia of said body, and means disposed within recesses in said body and adapted to engage the casing so that said body and casing may be withdrawn from said bore by said drill rod.

2. In drilling and shooting equipment for seismic prospecting including a drill rod, an explosion discharge tool secured to the drill rod and adapted to be lowered by said drill rod into a bore having a casing therein, said bore being provided with a drill hole at the base thereof, said tool comprising a massive body having an exterior diameter slightly less than the interior diameter of said casing, a cartridge mounted beneath said body, said cartridge comprising a cylindrical member of lesser diameter than said body and secured to the lower face thereof, an explosive charge confined within said cylindrical member, said cartridge being forced into said drill hole by said body whereby the force of the explosion of said charge will be directed downwardly into the earth due to the inertia of said body, means for detonating said charge, and means carried by said body to engage said casing so that said body and casing may be withdrawn from said bore by said drill rod.

3. In drilling and shooting equipment for seismic prospecting including a drill rod, an explosion discharge tool secured to the drill rod and adapted to be lowered by said drill rod into a bore having a casing therein, said bore being provided with a drill hole at the base thereof, said tool comprising a massive body having an exterior diameter slightly less than the interior diameter of said casing, a cartridge mounted beneath said body, said cartridge comprising a cylindrical member of lesser diameter than said body and secured to the lower face thereof, an explosive charge confined within said cylindrical member, and means for detonating said charge, said cartridge being forced into said drill hole by said body whereby the force of the explosion will be directed downwardly into the earth due to the inertia of said body.

4. In drilling and shooting equipment for seismic prospecting including a drill rod, an

explosion discharge tool secured to the drill rod and adapted to be lowered by said rod into a bore having a casing therein, said bore being provided with a drill hole at the base thereof, said tool comprising a massive body having an exterior diameter slightly less than the interior diameter of said casing, a cartridge detachably secured to the lower face of said body, said cartridge comprising a cylindrical member of substantially the same diameter as said drill hole, an explosive charge confined within said cylindrical member, and means for detonating said charge, said cartridge being forced into said drill hole by said body whereby the force of the explosion will be directed downwardly into the earth due to the inertia of said body.

5. In drilling and shooting equipment for seismic prospecting including a drill rod, an explosion discharge tool secured to the drill rod and adapted to be lowered by said rod into a bore provided with a drill hole at the base thereof, said tool comprising a massive body having an exterior diameter slightly less than the interior diameter of said bore, a cartridge mounted beneath said body, said cartridge comprising a cylindrical member of substantially the same diameter as said drill hole, an explosive charge confined within said cylindrical member, and means for detonating said charge, said cartridge being forced into said drill hole by said body whereby the force of the explosion will be directed downwardly into the earth due to the inertia of said body.
